UNITED STATES PATENT OFFICE.

SETH D. TRIPP, OF LYNN, MASSACHUSETTS.

WRAPPING-MACHINE.

SPECIFICATION forming part of Letters Patent No. 595,421, dated December 14, 1897.

Application filed July 31, 1896. Serial No. 601,167. (No model.)

To all whom it may concern:

Be it known that I, SETH D. TRIPP, of Lynn, county of Essex, State of Massachusetts, have invented an Improvement in Wrapping-Machines, of which the following description, in connection with the accompanying drawings, is a specification, like letters and figures on the drawings representing like parts.

This invention relates to wrapping-machines and is intended as an improvement upon the wrapping-machine shown and described in United States Patents No. 472,202, dated April 5, 1892, No. 516,136, dated March 6, 1894, and No. 548,677, dated October 29, 1895, which is especially designed for wrapping more or less spherical objects, such as oranges. Heretofore it has been customary in machines of this kind to place the orange or other article in a wrapper and then form a twist in the gathered-in edges of the wrapper, either by holding the article and twisting the gathered-in edges or by holding the gathered-in edges and rotating the article, and such a twist given to the gathered-in edges holds the wrapper in place.

I find in practice that by gathering in the edges of the wrapper and then firmly jamming them together or pinching them with jaws which are constructed and arranged to more or less corrugate, score, or indent them the wrapper having its gathered-in edges so jammed or pinched together will hold onto the orange or other article sufficiently for all practical purposes; and therefore my present invention consists in providing a wrapping-machine with a set of jaws or nippers adapted to firmly jam together and more or less corrugate, score, or indent the gathered-in edges of the wrapper.

The invention also consists in a holder for the orange or other article which is constructed and arranged to not only hold the article with the wrapper more or less wrapped about it while its edges are being gathered in and jammed together, but is also adapted to rise and fall so that it may approach the holder or rest upon which the wrapper is deposited, and while dwelling directly beneath it may receive the article and wrapper and then descend, and, furthermore, its construction is such that as the article is forced down into its grasp with the wrapper by a suitable

plunger provided for the purpose it will operate to lay the wrapper upon or about the article preparatory to having its edges gathered in and jammed together, thereby obviating the necessity of especially providing means for accomplishing this result.

Figure 1 shows in side elevation a sufficient portion of a wrapping-machine embodying this invention to enable the invention to be understood. Fig. 2 is a detail showing a side view of one of the arms of the orange-holder and its operating mechanism; Fig. 3, a detail showing the upper end of the orange-holding arms; Fig. 4, a detail of a modified form of orange-holding arm; Fig. 5, a detail of the upper end of the modified orange-holding arms; Fig. 6, a plan view of a set of jaws adapted to gather in the edges of the wrapper and jam them together and more or less corrugate or indent said gathered-in edges; Fig. 7, a cross-section of the set of jaws shown in Fig. 6, taken on the dotted line xx ; and Fig. 8, a detail showing the wrapper upon the orange or other article with its edges gathered in, jammed together, and more or less corrugated or indented.

The base A , stand or column b , rising therefrom and supporting the table or framework for the operating parts, the centering device, consisting of a ring u^7 and spring-acting fingers u^8 , down through which the orange or article is forced by the plunger c' , the arm c^3 , pivoted at c^4 to the stand b , and link c^2 , connecting its forward end with the lower end of the plunger c' , the stationarily-attached arms or brackets a' a^3 on the stand b , which afford bearings for the plunger c' , and the wires 80 , which project forward beneath the centering device and which hold the severed wrapper directly beneath said centering device, are all substantially as shown in the patents referred to, to which reference may be had.

The holder for the orange or other article which holds it and its wrapper while the edges of the wrapper are being gathered in and jammed together consists, essentially, of two arms s' , pivotally attached at s^2 to a cross-bar s^3 , secured to a vertical rod or bar s^4 , and said arms are bifurcated at their upper ends, presenting like forks arranged opposite to each other.

At the upper end of each arm a spiral spring

s^5 , as shown in Fig. 2, is provided, which extends from tine to tine of the fork, and spiral springs s^6 connect the tines of the opposite forks, so that a ring-like opening is produced at the upper end of the arms, which is shown as square in Fig. 3, although it may be of other shape, and is expansible.

The spiral springs s^6 join the two arms $s s'$ together, and adjustable limiting-stops s^7 on

- 10 a cross-bar s^8 , secured to the rod or bar s^4 , limit the movement of said arms toward each other. By connecting the upper end of the arms $s s'$ in this manner it will be seen that when the orange or other article and its wrapper are forced down into the grasp of the arms they will yield and will also lay the wrapper upon or about the article the full extent of the grasp, which, by referring to Fig. 1, will cover a little more than one-half the article.
- 15 20 These arms $s s'$ are designed to be raised and lowered in addition to yielding to receive the article and its wrapper, and to accomplish this result the rod or bar s^4 , to which they are pivotally connected, is movable vertically in bearings provided for it in the stationary brackets $a' a^3$, and said arms are guided by the cross-bars a^8 , there being two such bars provided, secured at one end to the stand b and at the other end to the brackets. As a means of
- 25 30 raising said rod or bar and arms supported by it long spiral springs s^9 are provided, attached at their upper ends to the stationarily-supported cross-bars a^8 and attached at their lower ends to a collar or flange s^{10} , adjustably
- 35 40 secured to the lower end of said rod or bar, said springs by their contractile force when permitted so to act lifting bodily the said rod or bar. The arms are thus raised to a point directly beneath the wrapper-holder 80 , so that the wrapper held by it and the article which is forced down through the centering device will be both forced into the grasp of said arms, which are disposed to receive them, and said arms in their passage pass up through
- 45 50 an opening formed by the jaws which are provided for gathering in and jamming together the edges of the wrapper, as will be described. To the lower end of the vertically-movable rod or bar s^4 a loop or strap s^{12} is secured, which passes down and around the actuating bar or lever c^3 for the plunger, so that said bar may be raised independently of the actuating-lever c^3 , but will be lowered by said actuating-lever.

- 55 After the arms $s s'$ have been raised to receive an article and its wrapper and then lowered, bodily carrying both the article and its wrapper within its grasp, it is necessary that the article shall be then held while the edges of the wrapper are gathered in and jammed together, and instead of providing special actuating devices for said rod or bar in order that it may dwell at such time while the gathering-in devices operate I have provided a locking device, shown as a latch s^{13} , pivoted at s^{14} to the bracket a^3 and pressed by a spring s^{15} into engagement with the flange

or collar s^{10} on said rod or bar, and an arm s^{16} projects from said latch s^{13} , which lies in the path of movement of the catch s^{17} on the actuating-lever c^3 , to be struck by said catch and thereby operated to move the latch and release the rod or bar. Thus when the rod or bar is depressed by the actuating-lever c^3 it will be caught and held by said latch s^{13} until released, and it is during this time that the gathering-in devices for the wrapper operate; also, it is necessary before releasing said locking device and permitting the arms $s s'$ to return to separate them sufficiently for the discharge of the wrapped article, and this is accomplished by extending the lower ends of the pivoted arms $s s'$ into the path of movement of two cam-like projections s^{18} , secured to the actuating-lever c^3 , so that when said actuating-lever is raised said cam-like projection s^{18} will strike the lower ends of said arms and by closing them together will separate the opposite ends of said arms for the discharge of the wrapped article. It will thus be seen that by the construction thus described the arms will rise and will receive in their grasp an article with its wrapper, which is more or less wrapped about it as it is received in its grasp, that said arms will then descend, carrying bodily said article and its wrapper, and that they will become locked in their lowermost position, where they will dwell while the devices which gather in and jam together the edges of the wrapper perform their work, and that said arms will then be separated and the wrapped article discharged, after which the locking device will be released and the arms permitted to rise for the next article. If desired, this holder may be employed in connection with a twisting device such as shown in the patents referred to, which is designed and intended to twist the gathered-in edges of the wrapper, as well as in connection with the many other devices shown in said patent.

The devices herein shown for gathering in the edges of the wrapper while the article with its wrapper is held by the holder consist of a set of jaws adapted to close together and gather in the edges of the wrapper and jam or pinch said edges tightly and by so doing will more or less corrugate or indent the wrapper, and by so gathering together the edges of the wrapper and corrugating or indenting them, as shown in Fig. 8, said wrapper will be sufficiently secured for all practical purposes. This set of jaws comprises two sets or piles of plates $v v$, each cut and made to present two arms, projecting at right angles with relation to each other; and said plates $v v$ of one set are joined together by a bolt v' , passing through them at the junction of the arms, and in order that said plates may be held more or less separated washers v^2 of suitable thickness are interposed between them, and, furthermore, in order that said plates may be separated with a certain degree of freedom a spring-

acting washer v^3 is provided for the bolt. The uppermost plate of the set of plates v^v is attached to the extremities of two bars v^4 , arranged in suitable guideways in the table 5 and adapted to be moved longitudinally in a horizontal plane, and when so moved the pile or set of plates v^v will be moved by them. The other set or pile of plates, which form a coöperative part of the set of jaws, likewise 10 consists of a pile of plates $v^5 v^5$, each cut to present two arms at right angles with relation to each other, like the plates v^v , and said plates $v^5 v^5$ are arranged in a pile opposite the plates v^v and so disposed with relation to said plates 15 v^v that the arms thereof will occupy positions between said plates v^v and move freely back and forth.

The plates $v^5 v^5$ are secured together at their junction by the bolt v^6 , and washers of 20 suitable thickness are interposed between the plates $v^5 v^5$, in order that they may be held separated sufficiently to receive between them the plates v^v , as aforesaid, and in order that said plates $v^5 v^5$ may yield somewhat bodily a 25 spring-acting washer v^7 is provided. The plates $v^5 v^5$ are secured to a bar v^8 , having its bearings in the table and movable longitudinally in parallelism with the bars $v^4 v^4$. It 30 is designed and intended that said plates v^v and plates $v^5 v^5$ shall move toward and from each other and thus constitute a set of jaws which gather in the edges of the wrapper and 35 jam them firmly together or pinch them, and as they are made quite thin and held separated the gathered-in edges of the wrapper will be more or less corrugated or indented or scored to better hold together.

As a means of moving the two sets of plates I have herein formed upon the adjoining sides 40 or edges of the bars $v^4 v^4$ rack-teeth, and upon each side of the central bar similar rack-teeth and two pinions $v^9 v^{10}$ are provided, turning 45 in suitable bearings in the table, one of which, as v^9 , meshes with the rack-teeth on the bars $v^4 v^8$ and the other of which, as v^{10} , meshes with the rack-teeth on the other bar v^4 and on the opposite side of said bar v^8 , and said 50 pinions are revolved in opposite ways, and the bars $v^4 v^4$ thus move one way, while the 55 bar v^8 will be moved in the opposite way. As a simple way of thus turning the pinions in opposite ways a double rack-bar v^{12} is provided, the rack-teeth upon one side of which engage the pinion v^9 and the rack-teeth upon 60 the other side of which engage the pinion v^{10} . The rack-bar v^{12} is reciprocated longitudinally to thus turn the pinions, and to thus reciprocate said rack-bar it is provided with an elongated slot v^{14} at one end, which serves as 65 a guide-slot for the bar, the main shaft passing through said slot and said bar thereby working upon said shaft as a rest or support, and upon one side of said bar a projection v^{15} is formed, which is engaged by a pin v^{16} , projecting from a disk v^{17} , secured to said shaft, and upon each revolution of said disk its pin

strikes said projection and moves the rack-bar one way a predetermined distance. During the revolution of said disk said pin v^{16} passes by said projection v^{15} , and when the 70 rack-bar is thus disengaged a spring v^{18} , attached at one end to the rack-bar and at the other end to the frame, acts to restore or return said bar. It is obvious that this set of jaws may be moved toward and from each 75 other in many different ways, so I do not desire to limit my invention to the particular way herein shown, although this particular way possesses some advantages owing to its simplicity of construction; nor do I desire 80 to limit the invention to any particular construction of jaws so long as they operate to jam the gathered-in edges of the wrapper together and more or less corrugate or indent them.

It is obvious that a set of jaws may operate to gather in and jam together and score the wrapper regardless of how the article to be wrapped may be held, and therefore I desire it to be understood that so far as said jaws 90 are concerned other parts of the machine may be constructed in any desirable way.

I claim—

1. In a wrapping-machine, a set of corrugating or indenting jaws consisting of two 95 piles of plates, the plates of each pile being separated to provide spaces in which the plates of the other pile work, one of said piles of plates comprising several two-armed plates connected together at the junction of 100 the arms thereof, leaving the extremities of the arms free to work in the spaces of the other pile, substantially as described.

2. In a wrapping-machine, a set of corrugating or indenting jaws consisting of two 105 piles of two-armed plates, the plates of each pile being connected together at the junction of the arms thereof, leaving the extremities of the arms free and separated to receive between them the arms of the other pile, and 110 means for moving said piles of plates toward and from each other, substantially as described.

3. In a wrapping-machine, a set of corrugating or indenting jaws consisting of two 115 piles of plates, means for holding the plates of each pile together and separated short distances apart to provide spaces in which the plates of the coöperating pile work, and a yielding device for each pile of plates constructed and arranged to permit the plates of each pile to separate more or less as required, 120 substantially as described.

4. In a wrapping-machine, a holder, means for raising and lowering it, means for forcing 125 the article with its wrapper into said holder when the latter is in its elevated position, a set of corrugating or indenting jaws, means for separating them to provide an opening for the passage of the holder, and means for 130 thereafter closing them together as the holder resumes its lowermost position to gather in

the edges of the wrapper, jam them together and more or less corrugate or indent them, substantially as described.

5. In a wrapping-machine, a holder, means for raising and lowering it, means for forcing the article with its wrapper into said holder when the latter is in its elevated position, a set of jaws, means for separating them to provide an opening for the passage of the holder, and means for thereafter closing them together as the holder resumes its lowermost position to gather in the edges of the wrapper, substantially as described.

6. In a wrapping-machine, a set of corrugating or indenting jaws consisting of two piles of separated plates yieldingly connected together, the plates of each pile being cut to present arms projecting at substantially right angles with relation to each other, and means for moving said piles of plates toward and from each other, substantially as described.

7. In a wrapping-machine, a set of corrugating or indenting jaws consisting of two piles of plates, the plates of each pile being formed to present arms projecting at substantially right angles to each other and said piles of right-angular plates being placed opposite each other, a bolt connecting the plates of each pile together at the junction of the right-angularly-projecting arms, leaving the extremity of the arms of each pile free and separated to receive between them the arms of the other pile, and means for moving said piles of plates toward and from each other, substantially as described.

8. In a wrapping-machine, a set of jaws adapted to gather in the edges of the wrapper and jam said gathered-in edges together, rack-bars connected to said jaws, two pinions in engagement therewith, and means substantially as described for revolving said pinions in opposite ways, substantially as described.

9. In a wrapping-machine, a holder having at its upper end an expansible unbroken ring-like opening into the grasp of which the orange or other article and its wrapper are forced, and by which said wrapper is more or less gathered about the article, substantially as described.

10. In a wrapping-machine, a rising-and-falling holder having at its upper end an expansible ring-like opening into the grasp of which the orange and its wrapper are forced and by which said wrapper is more or less gathered about the article, substantially as described.

11. In a wrapping-machine, a holder con-

sisting of arms connected together at their upper ends by spiral springs to thus form an expanding ring-like opening down through which the orange or other article and its wrapper are forced and by which said wrapper is more or less gathered about the article, substantially as described.

12. In a wrapping-machine, a holder consisting of a pair of arms connected together at their upper ends to form a ring-like opening thereat, into the grasp of which the orange or other article is forced with its wrapper, and means for separating said arms for the discharge of the wrapped article, substantially as described.

13. In a wrapping-machine, a holder consisting of arms having an expansible ring-like opening at their upper ends, means for raising and lowering said arms, and means for separating them for the discharge of the wrapped article, substantially as described.

14. In a wrapping-machine, a holder consisting of yielding arms, means for raising said arms, means for forcing the article with its wrapper into the grasp of said arms, means for lowering the arms, and means for separating them for the discharge of the wrapped article, substantially as described.

15. In a wrapping-machine, a holder consisting of yielding arms, means for raising them, means for forcing the article with its wrapper into the grasp of said arms, means for lowering the arms, carrying the article and its wrapper, a locking device for holding them in their lowermost positions, means for separating them for the discharge of the wrapped article, and means for releasing said locking device, substantially as described.

16. In a wrapping-machine, a holder consisting of yielding arms, means for raising them, means for forcing the article with its wrapper into the grasp of said arms, means for lowering the arms, a locking device for holding them in their lowermost position, gathering-in devices for the edges of the wrapper operative while the article is thus held by the arms, means for then separating said arms for the discharge of the wrapped article, and means for releasing said locking device for the return of the arms, substantially as described.

In testimony whereof I have signed my name to this specification in the presence of two subscribing witnesses.

SETH D. TRIPP.
